UNITED STATES PATENT OFFICE.

EMMET HORTON, OF DUNDEE, NEW YORK, ASSIGNOR TO GEORGE WILKIN,
OF SAME PLACE.

CRATE.

SPECIFICATION forming part of Letters Patent No. 350,134, dated October 5, 1886.
Application filed February 23, 1886. Serial No. 192,859. (No model.)

To all whom it may concern:

Be it known that I, EMMET HORTON, a citizen of the United States, residing at Dundee, in the county of Yates and State of New York, have invented new and useful Improvements in Crates, of which the following is a specification.

My invention relates to improvements in the Wilkin crate, patented December 22, 1885, used for picking and shipping fruit; and the objects of my improvements are, first, to so arrange the catches or locks of the crates that they cannot be disarranged or harmed in shipment, and that the shrinkage or swelling of the crate-heads shall not affect them in their action in transforming the picking-crates into a shipping-crate when more than one section is used; second, to prevent soiling of the fruit from the bottoms of the sections becoming muddy when used in picking, and to provide for circulation beneath the bottoms of the crates. I attain these objects by the arrangement of parts, as illustrated in the accompanying drawings, in which—

Figure 1 is a longitudinal vertical section on the line $x x$, Fig. 2, of two picking-crates as combined. Fig. 2 is an end view, in full, of same. Fig. 3 is an enlarged sectional view of crate ends and irons, showing more plainly the mode of attachment. Fig. 4 is a view of the section F in direction of arrow z, Fig. 3. Fig. 5 is a view of section B of crate-head in direction of arrow y, Fig. 3.

Similar letters refer to similar parts throughout the several views.

Instead of nailing the bottom slats, $c c c c$, to the lower edges of the head-pieces B B, as in the Wilkin crate above referred to, I insert their ends within a groove, a , cut across the inside of head-pieces B B, parallel with each other, for their reception. Below these grooves are downward projections b' of said head-pieces. These projections b' may be strengthened by nails, which hold in position slats, (shown by dotted lines, Fig. 2,) and will act as legs to support the crate. This construction permits circulation through the bottoms of crates when set down together or upon the floor, and prevents the bottom slats—that portion of the crate which rests over the fruit

when the crates are combined—from becoming muddy when a single crate is used as a picking-crate.

That the shrinking or swelling of the crate-heads may not affect proper engagement of the catches when combining, I have inserted in each end of the projecting central partition or handle, F, the spring-bolt S, which is thrown forward by its spring s' , also inserted with end compression about the guide-stem s^2 of the bolt, until checked by its shoulder s^3 striking against the cap-iron G, rigidly secured to the handle F, and through which the inclined portion s of the bolt projects in corresponding position to engage with and enter the opening O 65 in the iron D, which is sustained in position by being passed or hooked through the opening O^2 through the crate-head B.

As those portions of the irons intended to engage with each other when one crate is set down upon another should always remain equally distant, or nearly so, from the edges of the crate-head in their relative positions, I have arranged them in their attachment so that the swelling and shrinking of the head of the crate cannot affect materially such distance, as said irons move with the edges of the head in its expansion or contraction. Such is not the case when the bolt S is made in the form of a hook and hinged to the bottom of the head $8c$ of one crate, to engage with a hook fixed near a similar one at the bottom of the head of another crate, as in the Wilkin crate above referred to, and in which such shrinkage, with attachments of irons outside of the heads B B, 85 is found to be very detrimental to the crate in actual use.

In placing one crate upon the other the inclined portion t of the iron D serves to press back the bolt by slipping upon its inclined portion s , and, when passed below, the bolt S by its spring is thrown over the portion t of the iron D, and the crates are securely locked together, and when desired to unlock or disengage them it is necessary to insert the finger within the hollow opening O' of the iron D and push back the catch from off the portion t of said iron, the finger then resting against the shell r , when the upper crate may be readily lifted off.

Having thus fully described my improvement, what I claim, and wish to secure by Letters Patent, is—

1. In a crate, the raised portion F, having a spring-actuated bolt, in combination with crate-head B, having opening O through it, substantially as described.
2. A crate-head having a groove, a, slats e, inserted in the groove, projections b' below the bottom slats of the crate, and an opening, O, in combination with a crate having a central partition, F, provided with a spring-actuated bolt, S, substantially as described.

3. A crate having a raised portion, F, on one side and a recess or groove, e, Fig. 5, in its 15 opposite side, in combination with legs b' b', substantially as set forth.

4. The crate-iron D, having the inclined shoulder t and opening O above it, in combination with crate-head B, having opening O² 20 through it, and the raised part F, carrying the bolt S, substantially as set forth and described.

EMMET HORTON.
